(57) **CLAIM**

The ornamental design for a “crown-like plastic closure,” as shown and described.

DESCRIPTION

FIG. 1 is a perspective view showing my new design;

FIG. 2 is a front elevational view;

FIG. 3 is a rear elevational view;

FIG. 4 is a top plan view;

FIG. 5 is a bottom plan view; and,

FIG. 6 is a cross-sectional view taken along lines 6—6 in FIG. 4.

Any broken lines in the drawings depict probable environment only and form no part of the claimed design.
